UNITED STATES PATENT OFFICE.

INGEBORG M. JENSEN, OF CHICAGO, ILLINOIS.

CROCHET-NEEDLE.

1,303,327.

Specification of Letters Patent. Patented May 13, 1919.

Application filed July 18, 1917. Serial No. 180,885.

To all whom it may concern:

Be it known that I, INGEBORG MARIE JENSEN, a citizen of the United States, and a resident of Chicago, in the county of Cook and State of Illinois, have invented certain new and useful Improvements in Crochet-Needles, of which the following is a full, clear, and exact specification.

My invention is concerned with hand 10 crochet needles or hooks and is designed to produce a needle of the class described that will be easier to operate and which will do more regular and even work than is customary in hand work, the parts being so designed as in effect to control automatically 15 the size of the loop made in its operation and leave it in the correct shape so that the hook carrying the thread for the next loop can be most readily drawn through it by 20 the operator.

To illustrate my invention, I annex hereto a sheet of drawings, in which the same reference characters are used to designate identical parts in all the figures, of which,—

25 Figures 1 and 2 are a plan view and side elevation, respectively, of a needle embodying my invention, with the central portion thereof broken away; and

Figs. 3, 4, 5 and 6 are cross sections on 30 the lines 3—3, 4—4, 5—5 and 6—6, respectively, of Fig. 2.

In carrying out my invention, I make the body portion *a* preferably uniform in cross section throughout, and may place a hook 35 *b* at each end, preferably reversed. As seen in Fig. 6, the body portion *a* is substantially rectangular in cross section, with the corners rounded off and with its smaller dimension at right angles, or substantially so, to 40 the smaller dimension of the flattened hook *b*, so that the hook will be presented at the proper angle to the thread held in the left hand in the customary manner. The flattened body portion *a* by which large needles 45 are directly held will control this position of the hook, and where the needle is small, so that it is inconvenient to hold it directly by the body portion, I employ a holder co-operating with said flattened body portion, 50 such for instance as is shown in my application No. 147,885, filed February 10, 1917. The hook *b* is connected with the body by a portion *c*, generally rectangular at all 55 points in cross section, but with rounded corners, and varying in design in cross section, as is clearly indicated by the cross sec-

tions, as well as by the top-plan and side-elevation views. It has the sides *d* and *e* converging substantially uniformly from the wide body part to the narrow neck of the hook. The bottom *f* is substantially straight, but preferably slightly inclined relative to the axis of the body *a*. The upper part of *c* has two parts *g* and *h* inclined from the high point down to the body *a* and the neck of the hook *b*, respectively.

It will be noted that the maximum cross-sectional area of the connecting part *c*, as seen in Fig. 5, is slightly greater than that 70 of the body *a*, as seen in Fig. 6, and this is important, as it enables me to accumulate loops on the body portion, as is desirable in some forms of crocheting, without their being so tight on the body portion *a* as to bind, 75 so that they can be readily moved thereon. The location and size of the high point of the hump or connecting portion *c* are carefully designed to open up the loop to the proper extent to draw the thread back 80 through it as the hook reaches after the thread, and the high rectangular shape in cross section also shapes the loop so that it is of the proper design to allow the high, narrow hook to be drawn back through it, 85 carrying the thread for the new loop. For this purpose, it will be obvious that the length of the part *h* is important relative to the size of the needle, which, as it is thrust forward through the last loop after 90 the thread to form a new loop, should pass through the last loop until the point of the hump *c* is reached, thus opening up the loop to its maximum extent without any waste or excess movement of the needle.

By use of my novel design of crochet needle or hook, I find that it can be worked much more easily and does more even and uniform work with less skill on the part of the operator than any needles that have been 100 used prior to mine.

While I have shown and described my invention as embodied in the form which I at present consider best adapted to carry out its purposes, it will be understood that 105 it is capable of some slight modifications, and that I do not desire to be limited in the interpretation of the following claims except as may be necessitated by the state of the prior art.

What I claim as new, and desire to secure by Letters Patent of the United States, is:

1. A hand crochet hook having a flattened hook connected to the body portion by a connecting portion that is slightly higher at its highest point than the height of the hook, and which is tapered from said highest point down to the neck of the hook, and which is also tapered at right angles to the first taper from said highest point to said hook, substantially as described.
- 10 2. A hand crochet hook having a flattened body portion uniform in cross section, tapering by a connecting portion into a flattened hook, the narrower dimension of which is at right angles to the narrower dimension of the body portion, the thickest part of the connecting portion being thicker than the body portion and tapering from said thickest portion back to the thinner body portion and forward down to the neck of the hook, so that the greatest cross-sectional

area of the connecting part shall be equal to or slightly greater than the cross-sectional area of the body portion.

3. A hand crochet hook having a flattened hook with the flattened body portion at right angles thereto, the connection between the neck of the hook and the body portion being continuously tapered from the greatest width of the body portion to the neck of the hook, while at the right angles thereto is a hump tapered from its highest point to the neck of the hook in one direction and down to the thinner body portion in the other.

In witness whereof, I have hereunto set my hand and affixed my seal this 10th day of July, A. D. 1917.

INGEBORG M. JANSEN. [I. S.]
Witness:

JOHN HOWARD McELROY.
